UNITED STATES PATENT OFFICE.

JESSE WORREN CLEMENT, OF DUCHESNE, UTAH.

HAND-OPERATED IMPLEMENT.

Application filed June 29, 1922. Serial No. 571,624.

To all whom it may concern:

Be it known that I, JESSE W. CLEMENT, a citizen of the United States, residing at Duchesne, in the county of Duchesne and State of Utah, have invented certain new and useful Improvements in Hand-Operated Implements; and I do declare the following to be a full, clear, and exact description of the invention, such as will enable others skilled in the art to which it 10 pertains to make and use the same.

My invention relates to improvements in hand plows, cultivators, weeders and the like and has for one object to provide an 15 extremely simple and inexpensive device, yet one which may be very easily and advantageously operated.

Another object is to provide a novel construction whereby earth-working blades of 20 different sizes and shapes may be readily applied whenever necessary.

With the foregoing in view, the invention resides in the novel subject matter hereinafter described and claimed, the description 25 being supplemented by the accompanying drawing.

Figure 1 is a side elevation of a hand-operated implement constructed in accordance with my invention.

Figure 2 is a top plan view.

Figure 3 is a vertical transverse sectional view as indicated by the line 3—3 of Fig. 1.

Figure 4 is a side elevation of one of the frame forming bars.

Figure 5 is a side elevation of one of the implement carrying standards and a weeding or vine-cutting blade carried thereby.

Figure 6 is a front view of the parts shown in Fig. 5.

In the drawings above briefly described, the numeral 1 designates a supporting wheel having a suitable axle 2. The ends of this axle pass through the intermediate portions of a pair of side bars 3 whose rear

45 ends preferably incline in the manner shown and are curved upwardly and forwardly as indicated at 4. A pair of handles 5 are pivoted to the side bars 3 by means of bolts 6 which serve also to secure a spacing

50 bar 7 between said bars 3, as shown in Fig. 2. Bolts 8 are passed through the handles 5 and through any of a plurality of openings 9 formed in the bar ends 4, whereby the height of the handles may be adjusted as desired.

In front of the wheel 1, the side bars

3 are brought together into closely spaced parallel relation as indicated at 10 and are provided in their front ends with forwardly opening notches 11. The bar portions 10 may 60 well be held in proper spaced relation by a suitable spacer 12 and may be secured against opposite sides thereof by means of a rivet or bolt 13. An implement-carrying standard 14 is received between the 65 notched front ends of the bars 3 and is provided with oppositely extending stubs 15 received removably in the notches 11, said standard being also provided with an arcuate open-ended slot 16 concentric with the 70 stubs 15 to receive a clamping bolt 17 which extends through the bar ends 10. When the bolt 17 is loosened, the standard 14 may be swung about the stubs 15 as pivots, 75 thereby disengaging the slot 16 from said bolt 17 and permitting the standard 14 to be withdrawn forwardly from the notches 11, whereby another standard, carrying a blade of a different size and shape, may be substituted if desired. Furthermore, by 80 loosening the bolt 17, it will be seen that the inclination of the standard may be varied to meet requirements, for instance depth of cut.

In the present showing, the lower end of 85 the standard 14 carries a weeding and vine-cutting blade 18 which extends in opposite directions therefrom and is sharpened on all edges as indicated at 19. This is particularly advantageous when it is necessary 90 to move the implement both forwardly and rearwardly during operation, as the blade will cut both on its proceeding and receding strokes. Furthermore, by rocking the implement horizontally with the wheel 1 as 95 a fulcrum, it will be seen that the ends of the blade may be made to cut. By having the blade in front of the wheel 1, the operator is enabled to work the soil close to hills or plants.

The blade 18 forms an efficient weeder and it will also be understood that it is of advantage in cutting numerous kinds of vines, for instance, beans. Moreover, this blade may be successfully used for instance 105 as a carrot topper. In fact, the implement as a whole, when equipped with an appropriate set of different earth-working blades, may be used for a great number of gardening purposes.

Since excellent results are obtainable from the details disclosed, they are preferably 110

followed, but it is to be understood that within the scope of the invention as claimed, numerous minor changes may be made.

I claim:

- 5 1. A device of the class described comprising a frame including a pair of bars having their forward ends disposed in closely spaced parallelism, the extremities of said bars being provided with forwardly opening notches, and an implement-carrying standard arranged between the closely spaced portions of the bars and provided with trunnions removably received in said notches, said standard having an arcuate open-ended slot disposed in concentric relation with respect to said trunnions and said slot being engaged with a portion of said frame to permit adjusting of the standard or permitting it to be detached.
- 10 15 20 25 2. A device of the class described comprising a frame including a pair of opposed bars having their forward ends disposed in closely spaced parallelism, the extremities of the outer ends of the bars being formed with notches opening through said ends, an

implement carrying standard disposed between the spaced parallel portions of the bars, said standard being provided with intermediate laterally disposed trunnions removably seated in said notches to provide a fulcrum for the standard, the end of the standard adjacent said trunnion being provided with an elongated slot opening through the end, said slot being arcuate and substantially concentric with the trunnions, and a bolt passing through the closely spaced portions of the bars and slidably received in said slot.

3. In an implement of the class described, an implement carrying standard provided between its ends with right angularly disposed trunnions adapted to form pivots, the upper end of said standard being directed downwardly and into substantial parallelism with the body portion and said bent portion being provided with a slot opening through its free end.

In testimony whereof I have hereunto affixed my signature.

JESSE WORREN CLEMENT.
